CLAIM

The ornamental design for a brush cleaning mat, as shown and described.

DESCRIPTION

FIG. 1 is a front perspective view of a brush cleaning mat showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view thereof; and,

FIG. 9 is a rear perspective view thereof.

The dashed broken lines in the drawings represent portions of the brush cleaning mat that form no part of the claimed design.
